UNITED STATES PATENT OFFICE

170,106

WHEELED TOY

Harold D. Allen, East Hampton, Conn.

Application April 20, 1953, Serial No. 24,588

Term of patent 14 years

(Cl. D34—15)

To all whom it may concern:

Be it known that I, Harold D. Allen, a citizen of the United States, residing at East Hampton, in the county of Middlesex and State of Connecticut, have invented a new, original, and ornamental Design for a Wheeled Toy, of which the following is a specification, reference being had to the accompanying drawing, forming part thereof.

In the drawing

Fig. 1 is a side elevational view of a wheeled toy showing my new design;

Fig. 2 is an elevational view of the opposite side thereof;

Fig. 3 is a front elevational view.

I claim:

The ornamental design for a wheeled toy, substantially as shown.

HAROLD D. ALLEN.
